UNITED STATES PATENT OFFICE.

MATHEW P. BEDEL AND CHARLES A. MEURER, OF CINCINNATI, OHIO.

ADVERTISING DISPLAY DEVICE.

Application filed March 31, 1926. Serial No. 98,870.

This invention relates particularly to a device which will attract the eye for the purpose of drawing attention to a product to be sold.

5 An object of the device is to employ a totally unrelated subject to create or bring about the attention of a prospective customer to a product to be sold, and to display the product itself to best advantage whilst holding the attention through the agency of the unrelated subject matter.

10 A further object is to produce a device in which the mechanism employed adapts itself to innumerable combinations of toys or figures and their gyrations, to usage in store windows and in other locations wherein an easily moved and readily portable advertising medium and joy producer for young and old may be employed.

15 These and other objects are attained in the device described in the following specification and illustrated in the accompanying drawings in which:—

20 Fig. 1 is a side elevation of the device embodying our invention.

25 Fig. 2 is an end view, partially in section, on the line 2—2 of Fig. 1.

Fig. 3 is a plan view in section upon the line 3—3 of Fig. 1.

30 The device we have shown has its mechanism mounted in any suitable manner, as upon a base board 4, and enclosing the mechanism is a casing 5. The top of the casing carries a series of trapeze structures 6, 7 and 8 as well as two turntables 9 and 10 which carry the product or article to be displayed. Each of the trapeze structures carries a revolvably mounted horizontal bar 11, see Fig. 2, to which the arms of a propelling 35 manikin 12 are rigidly attached. Also upon bar 11 a trapeze 13 is pivotally swung. This trapeze in turn carries a manikin 14 which is pivotally attached thereto through its hands. By rotating the bar 11 the two manikins and the trapeze will be caused to operate in the performance of their gyrations as is very specifically described in U. S. Letters Patent No. 1,329,623 issued February 3, 1920, to Charles A. Meurer, who is one of the inventors herein. No claim is made in the present invention to this feature and only general descriptive reference is made for this reason thereto. However, in this present invention the rotation of bar 11 is attained by a pair of miter gears 15 and 16, the former being secured to bar 11 and

the latter to a vertical shaft 17 which occupies a hollow standard of the trapeze device. Each of the vertical shafts 17 is driven by a pair of miter gears 18 and 19, the latter gear of each set of which is secured to a longitudinally extending horizontal shaft 20 which is journalled in bearings 21, 22 and 23 on the base board.

60 Each of the turntables 9 and 10 is mounted on a respective shaft 24 and 25.

These shafts carry respective miter gears 26 and 27 which mesh with the gears 28 and 29, on a shaft 30, so that when one turntable is rotated the other one will rotate also. To 70 accomplish this we connect shaft 30 with shaft 20 by means of a short shaft upon which gears 31 and 32 are mounted, the former meshing with gear 26 and the latter with a gear 33 on shaft 20.

75 And now, in order to accomplish the driving of the acrobatic manikins and the turntables, we employ shaft 20 as the drive shaft and cause its rotation through the following mechanism. A motor 34 furnishes the power.

80 A worm 35 of the motor shaft drives through worm gear 36 on a jack shaft 37 which is mounted in bearings 38 and 39 and which carries a worm 40. This worm 40 in turn meshes with a gear 41 on a short shaft 42 which is journalled in a bearing 43 and carries on its opposite end a crank disc 44. This crank disc carries a connecting rod or pitman 45 and has provided thereon a series of teeth 46 which mesh with a gear 47 located 90 between two guiding discs 48 and 49 on a short shaft which carries a gear 50 meshing with a gear 51 on the drive shaft 20.

95 Thus power is transmitted throughout the structure in an unique and interesting manner, which, from the motor 34 to pitman 45 is always a continuous and unidirectional motion, but, because of the pitman 45, is changed into a reciprocating motion and thence into a reversing rotary motion starting with gear 47. This reversing rotary motion is carried through to shafts 17, 24 and 25, and results in a rotation of the bars 11 as well as the turntables 9 and 10 in one direction for a period of time and then in a 100 complete reversal and rotation of these elements in the opposite direction for a further and equal period of time. Of course the proportioning of speeds, number of rotations and other features may be governed by designing the mechanism and gear ratios to 105 meet the requirements.

In the use of the device, the operation of which applicants believe to be quite obvious, the goods to be displayed are placed on the turntables 9 and 10, as for example the cans 5 52 and 53 shown.

Having thus described our invention what we claim is:

1. A display device comprising a series of display mechanisms, a shaft adapted to operate each display mechanism, a drive shaft for said mechanism shafts, gears on said shafts for transmitting motion from one to the other, and means for transmitting oscillating rotary motion to the drive shaft, consisting of a crank, a pinion operatively connected with the drive shaft, a pitman connected at one end with the crank and having rack gear teeth formed at the opposite end for engagement with the teeth of the pinion, and means for rotating the crank.
2. A display device comprising a series of display mechanisms of one type, a series of display devices of another type, a shaft extending from and adapted to operate each display device, a drive shaft extending adjacent to and adapted to operate the display mechanisms of the first mentioned type, gears connecting the shaft and the drive shaft of the first mentioned type, a drive shaft extending adjacent and adapted to operate the display mechanisms of the second mentioned type, gears connecting the shafts and the drive shafts of the second mentioned type, means operatively connecting the drive shafts, a crank, a geared pinion, a pitman operatively connected at one end with the

crank and having rack teeth on its opposite end for cooperation with the teeth of the pinion, a connection operatively connecting the pinion with one of the drive shafts, and means adapted to drive the crank.

3. A display device comprising a series of display mechanisms of a type designed for indirect advertising, a series of display devices of a type designed for direct advertising and alternating in position with that of the first mentioned type, a shaft extending from and adapted to operate each display device, a drive shaft extending adjacent to and adapted to operate the display mechanisms of the first mentioned type, means operatively connecting the shaft and the drive shaft of the first mentioned type, a drive shaft extending adjacent to and adapted to operate the display mechanisms of the second mentioned type, means operatively connecting the shafts and the drive shaft of the second mentioned type, means operatively connecting the drive shafts, a crank, a geared pinion, a pitman operatively connected at one end with the crank, and having rack teeth at its opposite end for cooperation with the teeth of the pinion, means operatively connecting the pinion with the drive shafts, a source of power, and speed reduction mechanism operatively connecting the source of power and the crank.

In witness whereof, we affix our signatures.

MATHEW P. BEDEL.
CHARLES A. MEURER.
